United States Patent Office.

ALBERT J. POTTER, OF OMAHA, NEBRASKA.

Letters Patent No. 85,474, dated December 29, 1868.

IMPROVEMENT IN FARM-GATES.

The Schedule referred to in these Letters Patent and making part of the same.

To all whom it may concern:

Be it known that I, ALBERT J. POTTER, of Omaha, in the county of Douglas, and State of Nebraska, have invented certain new and useful Improvements in Farm-Gates; and I do hereby declare that the following is a full, clear, and exact description thereof, reference being had to the accompanying drawings, and to the letters of reference marked thereon, which form a part of this specification, in which is represented a perspective view of my gate.

The nature of my invention consists in the employment of a bevel-wheel, gearing into a segment of another bevel-wheel, in connection with cords, for opening and closing the gate, when arranged as hereinafter described.

To enable those skilled in the art to which my invention appertains, to make and use the same, I will proceed to describe its construction and operation.

In the accompanying drawing—

A represents an ordinary gate.

B B¹ B² B³, posts, secured in the ground at suitable distance apart, as seen in the drawing.

On each end of the end post *a* of the gate A are secured journals *b b'*, by which the gate is pivoted.

The journal *b* is passed through a hole made in the plate *c*, driven in the ground, and the journal *b'*, through a hole made in the shoulder *c'* formed on the bar C.

On the upper end of the end post *a* is secured a bevel-wheel, D, gearing into the segment of another bevel-wheel, D', attached to one end of the shaft *d*,

which passes through the cylindrical bar C, secured to the upper end of the main post B.

On the other end of the shaft *d*, a lever, E, is attached, which is provided, at its upper end, with a hole, through which the cords *e f g* pass.

The cord *e* is attached to the upper end of the lever F, which is pivoted at its lower end to the gate, and fastened to the bolt F'.

The cords *f g* are passed through holes in the metal plates *f' g'*, secured to the upper end of the posts B² B³.

The bolt F' is provided with a spiral spring, h, the object of which will be hereinafter described.

On each of the posts B¹ B² B³ are secured metal plates *m*, with a hole in the centre to receive the bolt F', the plates on the posts B² B³ being provided with a flange, so as to prevent the gate from swinging past the posts B² B³ when it is opened.

Having thus fully described my invention,

What I claim as new, and desire to secure by Letters Patent, is—

The gate A, bolt h, lever F, bevel-wheel D, cogged segment D', shaft d, cylindrical bar C, lever E, cords e f g, and posts B B¹ B² B³, all combined, constructed, arranged, and operated substantially as and for the purpose set forth.

In testimony that I claim the foregoing as my own, I affix my signature, in presence of two witnesses.

Witnesses: ALBERT J. POTTER.

WALLACE HOMEE,

C. L. BRISTOL.
